UNITED STATES PATENT OFFICE.

PETER T. HYDEN AND ADOLPH LARSON, OF CHICAGO, ILLINOIS.

ROTARY STEAM-ENGINE.

SPECIFICATION forming part of Letters Patent No. 252,773, dated January 24, 1882.

Application filed May 16, 1881. (No model.)

To all whom it may concern:

Be it known that we, PETER T. HYDEN and ADOLPH LARSON, subjects of the Kingdom of Sweden, residing at Chicago, in the county of Cook and State of Illinois, United States of America, have invented a new and useful Improvement in Rotary Steam-Engines, of which the following is a specification.

The objects of our invention are to provide a rotary steam-engine which is cheap and effective, and will give great power with a small amount of steam; and the invention consists in the construction and arrangement of parts, as hereinafter more fully described and claimed.

Figure 1 is a side view of our invention, showing port-holes for entrance of the steam. Fig. 2 is an inside view of cylinder B, showing steam-passage W. Fig. 3 is a sectional view on the line x x of Fig. 1 with spring attachment for operating valve. Fig. 4 is a section through y y of Fig. 1. Fig. 5 is an outside view of cylinder B with the cap F removed. Fig. 6 is a section on the line z z of Fig. 2. Fig. 7 is a wheel attached to shaft E, to operate the valve attachments. Fig. 8 is a side view of piston. Fig. 9 is a front view of same. Fig. 10 is the packing of piston.

Similar letters refer to similar parts throughout the several views.

A represents our new rotary steam-engine. B is one of the cylinder-plates or ends forming the steam-chamber. C is the other cylinder-plate.

a a are holes in cylinder B for the reception of pins b b of cylinder C. B and C are put together and held by pins b b and holes a a.

D is the piston, made in the shape as shown in Figs. 8 and 9.

E is the shaft which carries the piston. E passes through holes or bearings c c in the center of B and C.

d d is the packing at the end of the piston D. It is provided with rings secured by bolts or otherwise, so as to make a good packing.

F is a cap rigidly attached to outside end of cylinder B, and is provided with two inlets or openings, G G, for the entrance of the steam. G G are connected to pipe r from boiler, which pipe has a cock, t, for the purpose of shutting off the steam from one or the other of the inlets G G, as may be desired. The end of B is

cut out, with ledges or rests h h for the cap F, and leaving beneath F an opening, H, in which the valve L slides, and also with an opening or slit, K, in the center, in which one portion 55 of the valve L moves.

L is what we call a "sliding valve," and is composed of two pieces rigidly attached together at right angles. The pieces are lettered l and k. l slides in H and k in opening K. 60

g g are small passages from opening H into the inside chamber of the engine. One is on each side of slit K, and are for the passage of the steam into the inside of the chamber. The slit K is also in the top of the cylinder C 65 at its junction with B.

M M are outlets or exhaust-ports in C for the steam to escape, and may be placed at any convenient point on C. N is the cover or top at valve end of cylinders B and C, rigidly attached. 70

W is a passage cut out curved upon the inside of the cylinders B and C, and is for the passage of the steam which works the piston.

J is a rod connected to the valve L at one 75 end and at the other to the arm R.

O is a wheel on shaft E, and made as shown in Fig. 7.

P is a rod which works in connection with wheel O, and is connected to arm R; or P and 80 R may be made in one piece.

s s are shoulders or bearings, through which rod P works or slides, and against which spring T has a bearing.

T is a spiral spring around rod P, and is for 85 the purpose of throwing rod P back. This attachment of rods, springs, and arms is for the purpose of moving valve L up and down. This arrangement may be dispensed with. In that case the piston will be made in the shape 90 as shown by the dotted lines in Fig. 8. The rod J will only be used. Upon it will be a spring, V. This piston will force the valve L up, and the spring will move it back.

Q Q are rings, one on each side of the piston D, which is grooved out, and the rings are inserted so as to project a little into grooves in B and C, and are for the purpose of packing. Q Q are shown in Fig. 10.

The arrangement of the cock and the two 100 inlets is for the purpose of moving the piston in either direction. If the steam is let in

one port, it will move in one direction, and if let in the other port it will move in the other direction; but the steam is let in only through one port at a time.

5 The manner of operation is as follows: The cylinders B and C are attached together with all the parts in their proper position. The engine is attached to the boiler and the steam turned on. The cock t is turned so as to allow 10 the steam to pass into one of the ports, and it passes down through passages g into the inner chamber of the cylinders and moves around the passage W, forcing the piston D before it until the steam comes to the outlet M, when it 15 will escape, and this will revolve the piston which revolves the shaft. The wheel O, revolving on the shaft E, will force the rod P up, which will carry the valve L up and close the port, preventing the steam from entering, and 20 the spring T will force the rod back, which will carry back the valve L and open the inlet-port, so that the steam may enter, and this operation can go on as long as desired. In the event the wheel O and its connections are dispensed 25 with the piston D will force the valve up and close the port, and the spring V will open the same. By simply turning the cock t the steam will be let in at the other port and the direction of the movement of the piston changed 30 immediately. The ports are open or closed by l of the valve L, l being about half the size of H, so that when down it will not cover the ports, but when raised it will.

Any gearing can be attached to the shaft, 35 and any machinery operated as may be desired.

What we claim as new and original, and desire to secure by Letters Patent, is—

1. In a rotary steam-engine, the cylinder-plate C, provided with pins b b, slit K, steam

passage or chamber W, bearing c, outlets M 40 M, and cover N, in combination with cylinder-plate B, substantially as described and shown, and for the purpose set forth.

2. In a rotary steam-engine, the cylinder-plate B, provided with holes a a, steam 45 passage or chamber W, bearing c, slit K, steam-passages g g, chamber H, ledges h h, and cap F, having inlets G G, in connection with cylinder-plate C, and in combination with valve L, substantially as described and specified, and 50 for the purpose set forth.

3. The sliding valve L, composed of pieces l and k, at right angles to each other, in combination with chamber H and slit K, whereby the steam is let in and shut off, substantially 55 as described and shown.

4. The combination, in a rotary steam-engine, of the rod P, arm R, spring T, shoulders s s, rod J, and valve L, substantially as 60 described and shown.

5. The combination, in a rotary steam-engine, of the cylinder-plate C, provided with pins b b, slit K, steam-passage W, outlets M 65 M, cover N, and bearing c, the cylinder-plate B, provided with holes a a, bearing c, steam-passage W, slit K, steam-passages g g, chamber H, cover N, the cap F, having inlets G G, pipe r, with regulating-cock t, valve L, having ports l and k, rod J, spring V, arm R, rod P, spring T, shoulders s s, wheel O, shaft E, 70 and piston D, having ends d d and packing-rings Q Q, all substantially as described and shown, and for the purpose set forth.

PETER T. HYDEN.
ADOLPH LARSON.
